SEWING MACHINE

Fred Ashworth, Beverly, Mass., assignor to United
Shoe Machinery Corporation, Paterson, N. J.,
a corporation of New Jersey

Application May 27, 1932, Serial No. 613,822

10 Claims. (Cl. 112—45)

The present invention relates to wax thread shoe sewing machines, and more particularly to a work channelling device for use in connection with a McKay type shoe sewing machine, which 5 type of machine comprises a straight hook needle and a shoe supporting horn arranged to extend within the shoe, and a needle threading whirl located in the horn.

The object of the present invention is to produce an improved mechanism for supporting and actuating a grooving or channelling knife for machines of the type referred to.

With the above and other objects in view, the present invention contemplates the provision, in a 15 shoe sewing machine, of a work grooving or channelling knife supported upon a carrier arranged to be moved toward and away from the work, and in the direction of work feed, which carrier supports and actuates a work piercing instrument to 20 feed the work, and imparts a cutting action to the knife during the return movement of the carrier after the feeding movement of the work piercing instrument. The channelling knife is preferably so connected with the carrier as to move with 25 relation thereto as the carrier moves toward the work, and a spring is provided, acting to cause the knife to yieldingly engage the work. The knife is prevented from producing too deep a 30 channel by a stop member associated with the carrier to arrest the movement of the knife under the action of the spring.

The machine to which the present invention is applied is substantially the same as that described in applicant's copending application Serial 35 No. 394,770, filed September 24, 1929, in which there is disclosed a machine of the McKay type having a straight hook needle, a rotary work supporting horn, a presser-foot, a feed point, a shuttle, and various other necessary elements for 40 forming stitches and feeding the work. This machine, as previously constructed, is arranged with a carrier of the type indicated for operating the feed point. The movement of the carrier in this 45 machine toward and from the work is controlled in part by the position of the presser-foot while in engagement with the work, so that a uniform penetration of the feed point will always take place, and when the presser-foot is raised at the 50 end of the seam, the feed point will also be disengaged from the work. According to another feature of the present invention, the use of a carrier operated in this manner insures that the work grooving knife will automatically be disengaged from the work simultaneously with the

disengaging movement of the presser-foot and feed point at the end of the seam.

Further features of the invention consist of certain constructions, arrangements and combinations of parts, the advantages of which will be obvious to one skilled in the art from the following description.

In the drawings illustrating the invention in its preferred form, Fig. 1 is a view in front elevation of a portion, including the stitch-forming 10 and work feeding devices, of a sewing machine embodying the present invention; Fig. 2 is a corresponding view on an enlarged scale of a portion of the mechanism shown in Fig. 1; Fig. 3 is a view in side elevation on a slightly reduced scale, 15 and partly in section, of the devices illustrated in Fig. 2; and Fig. 4 is a view in section taken along the line 4—4 in Fig. 2.

The machine illustrated in the drawings comprises a straight hook needle 2, a rotary work 20 supporting horn 4, having a needle threading whirl 5, a presser-foot 6, a feed point 8, a rotary shuttle 10, and a loop spreader 12 for engaging the loop of thread with the beak of the shuttle. The presser-foot is actuated intermittently to 25 clamp and release the work against the rotary horn 4, while the feed point 8 engages and feeds the work alternately with the engagement of the presser-foot, as is usual in this type of machine.

The presser-foot 6 is supported at the end of 30 a reciprocating presser-foot bar 14. The presser-foot is resiliently held in downward position and is intermittently retracted a uniform distance from the work by mechanism, indicated generally at 16 actuated from a shaft 18 which, in turn, 35 is oscillated in suitable timed relation with the other stitch-forming devices. The feed point 8 is clamped at the lower end of a carrier 20, slidably mounted for vertical movement toward and away from the work in a guide frame 22 which 40 is pivotally mounted on the main frame of the machine.

The frame 22 is oscillated about its pivot to 45 impart feeding movements to the feed point 8 in the line of feed by means of the feed lever 24 which is loosely mounted on a hub supported at the forward end of a rock shaft 26. The rock shaft is oscillated by connections to a main sewing shaft, as more clearly described in the co-pending application referred to.

The feed point is moved into and from engagement with the work by the sliding movement of the feed point carrier 20 in the frame 22, through connections to the presser-foot actuating rock shaft 18. These connections comprise 50 55

a link 28 pivotally connected at one end with the upper end of the feed point carrier 20 and at the other end with the arm of a bell crank 30 fulcrumed on a shaft 32 secured to an arm 34, a 5 link 36 connected between the other arm of the bell crank 30 and an arm 38 connected with the presser-foot actuating shaft 18, the arrangement being such that the feed point is moved into engagement with the work while the presser-foot 10 releases the work. The arm 34 which carries the bell crank 30 is fixed at one end to a shaft 40 rotatable in the frame of the machine and at the other end is connected to move with the reciprocating presser-foot bar 14 so that the lowermost 15 position of the feed point, while in engagement with the work, is determined by the position of the presser-foot, and as the presser-foot is raised from the work at the end of the seam, the feed point is also separated from engagement with the 20 work.

At the end of a seam, or at other times, the presser-foot, together with the feed point carrier, and the feed point, may be retracted from the work automatically or by means of a hand lever 25 27. The lever is provided with an abutment 42 adapted to engage a pin 43 carried on the presser-foot bar 14. All of the parts above briefly referred to are constructed and arranged in the same manner and operated by mechanism similar to 30 that illustrated and described in said previously mentioned application.

In accordance with the present invention, a work grooving knife 44 is provided, pivotally mounted at its upper end on a short horizontal 35 U-shaped link 45 pivoted in turn at 46 to and surrounding the lower end of the feed point carrier 20. The lower end of the work grooving knife extends loosely through an opening 47 in the feed point 8 near its work engaging end. The 40 knife is resiliently held in engagement with the work by a compression spring 48 secured at its upper end in an opening formed in the feed point carrier and pressing at its lower end against the bottom of a similar opening in the link 45. By 45 this means, the grooving knife is maintained in engagement with the work while the feed point is intermittently disengaged, as in the ordinary stitching operation. When the feed point moves into engagement with the work to cause the work 50 to be fed, the spring 48 yields and allows the knife to remain stationary without injuring the work and during the feeding movement of the feed point, moves with the work without any cutting action.

55 To prevent the knife from forming a channel under the action of the spring 48, deeper than desired, an adjustable stop screw 49 is threaded into the feed point carrier and a lock nut arranged to prevent change of adjustment. The inner end of the stop screw 49 engages a portion 50 extending upwardly from the pivoted end of the link 45 in a position to prevent downward movement, beyond the position to which the stop screw is adjusted, of the end of the link carrying 60 the channel knife. The stop screw also serves at the end of the seam to cause the channelling knife positively to be withdrawn from the work as the presser-foot and feed point are retracted.

In operation, the feed point is caused to move 70 downwardly from the position shown in Fig. 1, and to be retracted alternately, into and out of engagement with the sole of a shoe, indicated at 52. At the same time, the presser-foot is being moved upwardly and downwardly in opposite directions from the movement of the feed point

toward and from the work. The stop screw 49 on the feed point carrier is adjusted to strike the portion 50 of the link 45 at exactly the point at which the feed point reaches the upper limit of its travel, according to the depth to which the channel is desired to be cut. As the feed point engages the work, the grooving knife remains stationary until the work feeding movement begins, during which time it moves with the work so that no cutting action of the knife takes place. 10 The feed point is then disengaged from the work and moved in a direction opposite to that of work feed to its original position. While the feed point is being disengaged from the work, the spring 48 acts to maintain the knife 44 stationary and in engagement with the work. While the feed point is being backfed, the knife moves with it against the work to form a continuous channel by reason of the engagement of the knife against the side of the opening 47 in the feed 20 point. This occurs while the work is rigidly clamped between the presser-foot and the work supporting horn without interfering in any way with the operation of the other stitch-forming and work feeding devices. At the end of the 25 seam, the presser-foot, feed point, and channelling knife may simultaneously be retracted to disengage the work as indicated.

Having thus described the invention, what is 30 claimed is:

1. A sewing machine having, in combination, stitch-forming and work feeding devices including a work support, a presser-foot, a carrier arranged to be moved with relation to the presser-foot toward and away from the work and in the direction of work feed, and a work piercing instrument and a work grooving knife mounted on the carrier to operate on the work during sewing of a seam. 35

2. A sewing machine having, in combination, stitch-forming and work feeding devices including a work support, a presser-foot, a needle, a feed point carrier arranged to be moved in the direction of work feed, a feed point secured to the carrier, a work grooving knife mounted on the carrier for movement toward and from the work relative thereto, and means for actuating the grooving knife to engage and cut the work during the back feeding movement of the feed point carrier, and while the presser-foot engages the work. 45

3. A sewing machine having, in combination, stitch-forming and work feeding devices including a work supporting horn and a presser-foot, a straight hook needle, a feed point carrier arranged to be moved toward and away from the work and in the direction of work feed, a feed point secured to the carrier, a work grooving knife mounted on the carrier for movement relative to the feed point in a direction toward and away from the work and for movement with the feed point in the direction of work feed, and resilient means arranged to cause the grooving knife to yieldingly engage the work while the feed point is moved away from the work. 50

4. A sewing machine having, in combination, stitch-forming and work feeding devices including a work supporting horn and a presser-foot, a straight hook needle, a feed point carrier arranged to be moved toward and away from the work and in the direction of work feed, a feed point secured to the carrier, a work grooving knife mounted on the carrier for movement relative to the feed point in a direction toward and away from the work and for movement with the feed point in the direction of work feed, resilient means arranged 55

to cause the grooving knife to yieldingly engage the work while the feed point is moved away from the work, and a stop, acting between the feed point carrier and the grooving knife for limiting the movement of the knife by the resilient means toward the work while the feed point is moved away from the work.

5. A sewing machine of the McKay type having, in combination, stitch-forming and work feeding devices including a rotary work supporting horn and a presser-foot, a straight hook needle, a feed point carrier arranged to be moved toward and away from the work and in the direction of work feed, a feed point secured to the carrier, a work grooving knife mounted on the carrier for movement relative to the feed point in a direction toward and away from the work, and for movement with the feed point in the direction of work feed, connections for actuating the stitch-forming and work feeding devices to cause the grooving knife to engage and cut the work during the back feeding movement of the feed point, and while the presser-foot engages the work, and means for raising simultaneously the presser-foot, the feed point and the grooving knife from the work at the end of the seam.

6. A sewing machine of the McKay type having, in combination, stitch-forming and work feeding devices including a rotary work supporting horn and a presser foot, a straight hook needle, a feed point carrier arranged to be moved toward and away from the work in the direction of work feed, a feed point secured to the carrier, a work grooving knife mounted on the carrier for movement relative to the feed point in a direction toward and away from the work, and for movement with the feed point in the direction of work feed, connections between the presser-foot and the feed point for causing the feed point to penetrate the work uniformly according to the position of the presser-foot on the work, mechanism for raising the presser-foot from the work at the end of a seam, and means for actuating the stitch-

forming and work feeding devices to cause the grooving knife to engage and cut the work during the back feeding movement of the feed point and while the presser foot engages the work.

7. A sewing machine having, in combination, 5 stitch-forming devices including a work support, a presser-foot, a carrier arranged to be moved toward and away from the work and in the direction of work feed, a feed point on the carrier having an opening adjacent its work engaging end, 10 and a work grooving knife secured to the machine and extending through the opening in the feed point to engage and cut the work during the back feeding movement of the feed point.

8. A sewing machine having, in combination, 15 stitch forming devices including a work support, a presser-foot, a feed point having an opening adjacent its work engaging end, means for actuating the feed point to feed the work, and a work grooving knife secured to the machine and extending through the opening in the feed point to cut the work during the back feeding movement of the feed point.

9. A sewing machine of the McKay type, having, in combination, stitch forming and work feeding 25 devices including a rotary work supporting horn and a presser-foot, a straight hook needle, a feed point movable in the direction of work feed, means for actuating the feed point to feed the work, and a work grooving knife movable in the direction of work feed arranged to cut the work during the back feeding movement of the feed point.

10. A sewing machine of the McKay type having, in combination, stitch forming and work feeding devices including a rotary work supporting horn and a presser-foot, a straight hook needle, a feed point movable in the direction of work feed, a grooving knife mounted to move relatively to the feed point and actuated by the feed point during the back feeding movement of the 40 feed point to cut the work.
